HARRY HARTMAN AND JOSEPH A. BROWNE, OF LOS ANGELES, CALIFORNIA; SAID
BROWNE ASSIGNOR TO SAID HARTMAN

EXPANSION CLASP FOR BRACELETS AND THE LIKE

Application filed March 5, 1930. Serial No. 433,413.

Our invention pertains particularly to the manner of the expansion of chain links in a clasp whereby the clasp may be opened and the links extended to allow fitting the bracelet over the hand and then the links may be folded to fit inside of the clasp.

An object of our invention is the construction of a clasp having a hinge whereby the lid of the clasp may be tilted open and a series of folding links which are held in the clasp may be extended. The chain of the bracelet is connected to the clasp at one end and to one of the folding links at the other end so that when the clasp is opened and the links are fully extended the bracelet may readily be slipped over the hand, then the links are folded together and the clasp closed, thus holding the bracelet tight around the wrist. This type of bracelet may be used 20 for wrist watches or the like.

One of the features of our invention is in the manner of attaching the one chain end to the clasp so that the pull on the clasp operates to hold the clasp tightly closed and avoid 25 accidental opening. Another feature is in the use of a slip link which may slide longitudinally in the clasp and thus facilitate unlatching of the bracelet without the necessity of having a large number of folding links.

Another detail feature of our invention is having one or more of the links made with 30 double link strips and adjustable to shift to different positions to form an extension link whereby this extension link may be shortened or lengthened and thus give a fine adjustment to fit the wrist snugly when the bracelet is folded.

Our invention is illustrated in connection 40 with the accompanying drawings, in which,

Fig. 1 is a perspective view of the expansion clasp in the closed position;

Fig. 2 is a longitudinal section through the clasp of Fig. 1;

Fig. 3 is a plan of the clasp with the links 45 extended and the cover removed;

Fig. 4 is a longitudinal section of the expanded links of Fig. 3.

In the drawings, the clasp is designated 50 generally by the numeral 11. This has a channel-shaped base 12 having a web sec-

tion 13 to fit against the wrist and two marginal flanges 14. Each of these flanges has an inturned sectional rim 15. The web 13 is made in a slight arc of a circle and the flanges 14 are concentric with the curvature of the 55 web. The cover 16 of the clasp has a top section 17 and two inwardly extending flanges 18. The flanges 18 and the flanges 14 are connected by a pintle pin 19 at one end.

A feature of our invention is the inwardly 60 turned end 20 of the cover which is attached to a short link 21 and this latter if desired to a longer link 22 at one end of the chain. The chain is usually made of similar types of links which extend completely around the 65 wrist, or if a wrist watch is used the chains have devices for attaching to the wrist watch. The opposite end of the flanges 18 have a notch 23 for a purpose hereinunder detailed.

We employ a slip link 24 which has a pair 70 of slots 25 therethrough; these slots being engaged by inwardly extending tongues 26 which are pressed inwardly of the clasp from the web section 13 and bent over, thus guiding the link 24. This link follows the curvature of the web 13. A fixed link 27 is secured 75 to the link 24 by a hinge 28, allowing folding of the link 27 on top of the link 24 and when partly folded the link 27 has a curvature concentric with the web 13 and also the curvature of the link 24. An extension link 29 is 80 formed of an inner strap 30 and an outer strap 31. The inner strap is connected to the link 27 by a hinge 32. The outer strap is illustrated as having three counter-sunk perforations 33 therethrough and the inner strap is illustrated as having four screw threaded 85 perforations 34 and there are two screws 35 with counter-sunk heads which may be secured in two of the aligned perforations 33 and 34. Thus by changing the screws the link 29 may be extended slightly.

This link has an inwardly turned end 36 which is indicated as having an eye 37 which attaches to a short link 38 similar to the short link 21 and the rest of the chain may have alternately a long link 39 corresponding to the link 22 and a series of short links corresponding to the links 21 or 38. When the bracelet is extended to slip over the hand the 100

links occupy the position shown in Figs. 3 and 4, in which it will be noted that the slip link 24 is pulled out until the ends of the slots engaging the tongues 26 limit the outward pull.

5 If it is desired to give additional adjustment the screws 35 may be removed and inserted in different perforations in order to lengthen the extension. Manifestly if in the 10 first place this link is too long, it may be shortened. In housing the extension part of the bracelet the slip link 24 is slid into its housing in the lower part of the clasp and the link 27 is then hinged over the link 24. 15 Then the extension link naturally occupies a position on top of the link 27. All of the links when housed slip underneath the sectional rim 15 and are thus snugly held in the lower part of the clasp housing. The pintle 20 of the hinge 28 has end extensions 40 which are engaged by the notches 23 on the side flanges 18 of the cover part of the clasp. This engagement is such that the pull on the clasp by the chains at each end tends to 25 tighten the locking of the cover on the base part of the clasp. When the extension folding links are housed in the clasp they occupy the position shown in Fig. 2.

Various changes may be made in the principles of our invention without departing 30 from the spirit thereof as set forth in the description, drawings and claims.

We claim:

1. In an extension clasp, a base portion and 35 a cover portion pivotally connected together, a chain attached to the cover portion, a plurality of folding links one of which is attached to the base portion, said links when folded fitting in the base portion, a chain attached to the endmost link, and means to vary 40 the length of at least one of the folding links, the link connected to the base portion of the clasp having a sliding connection therewith.

2. In an extension clasp, a base and a cover 45 hinged together, a plurality of links, one of which has a sliding connection with the base and said links being hingedly connected together to fold upon one another after the slip link is slid into the base, means 50 in the base to retain the links in folded position and the said cover being adapted to encase the said links in the base, and a chain end attached to the cover and another chain end attached to one of the links, the means to 55 retain the folded links in the base comprising a sectional rim portion on the base adapted to engage the links when folded and slid into the base.

3. In an extension clasp, a channel-shaped 60 base, a slidable link connected to the base, means to limit the outward sliding movement thereof, a second link hinged to the slidable link and adapted to fold thereover, the base having side flanges with inwardly turned sectional rims adapted to engage the folded links,

a cover hinged to the base and adapted to enclose the said folded links, a first chain end connected to the cover and means to connect a second chain end to the second link.

4. In an extension clasp as claimed in claim 70 3, the cover having a channel-shaped structure with inwardly extending flanges with notches therein and the hinged connection of the slidable link and the second link having an extended pintle, such extensions adapted to 75 fit in the said notches.

5. In an extension clasp, a base, a cover hinged to the base, a slip link having longitudinal slots therein, tongues secured to the base and fitting in the said slots forming a guide 80 and a limit to the sliding movement of the slip link, the cover being adapted to house the slip link when telescoped in the base, a first chain end connected to the cover, a plurality of links hinged together, having one 85 of such links hingedly connected to the slip link a second chain end connected to the link most remote from the slip link, said remote link being extensible and being formed in at least two parts with means to adjust the relative position of such parts.

6. In an extension clasp, a channel-shaped base having tongues thereon, a slip link having slots therein connected to the base by said tongues on the base extending through the 90 slots, said tongues forming a limit to the sliding motion of the slip link, a second link hinged to the slip link and a third link hinged to the second link, the second link folding over the slip link and the third link over the 1 second link, the base having side flanges with sectional rims to retain said links in a folded position, a cover hinged to the base and having a first chain end connected thereto and a second chain end connected to the third link.

7. In an extension clasp as claimed in claim 6, the third link being formed of a pair of strap-like sections superposed one on the other and having a plurality of perforations with screws to adjust said strap-like sections 1 by engaging the screws in different perforations.

8. In an extension clasp, a base, a plurality of links hingedly connected together and one of which is secured to the base, one of said hinges having a pintle with extensions thereon, a cover hinged to the base and having inwardly extending flanges with notches to accommodate the said extensions of the pintle, a first chain end connected to the cover and a second chain end connected to one of the links most remote when extended from the base.

9. In an extension clasp, a base, a cover hinged thereto, a slip link slidably connected to the base, a second link hinged to the slip link, a third link hinged to the second link, said links being foldable upon one another after the slip link is slid into the base, the cover being adapted to extend over the folded

links, a first chain end connected to the cover and a second chain end connected to the third link.

10. In an extension clasp, a base, a cover hinged thereto, a slip link slidably connected to the base, a second link hinged to the slip link, a third link hinged to the second link, said links being foldable upon one another after the slip link is slid into the base to extend over the folded links, a first chain end connected to the cover and a second chain end connected to the third link.

11. In an extension clasp as claimed in claim 10, one of the said links being formed in two parts to form an extension, and means to adjustably connect said two parts together.

In testimony whereof we have signed our names to this specification.

HARRY HARTMAN.

JOSEPH A. BROWNE.
